Primary Examiner — Daniel Bui*Assistant Examiner* — Khawaja Anwar*(74) Attorney, Agent, or Firm* — NSIP Law(57) CLAIM

We claim the ornamental design for a shelf for wine refrigerator, as shown and described.

DESCRIPTION

FIG. 1 is a front perspective view of a shelf for wine refrigerator showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a cross-sectional view taken along the line 8-8 of FIG. 6.
